AUTOCLAVE

Emil R. Schipanski, Gardena, Calif.

Application September 11, 1946, Serial No. 696,290

20 Claims. (Cl. 21—98)

1

My invention relates generally to equipment for sterilizing surgical gowns, dressings, instruments, and the like, and more particularly to autoclaves wherein such sterilization is accomplished by the use of steam under pressure.

Autoclaves for the above purpose have usually been constructed principally from heavy metal castings with the steam lines associated therewith mounted on the outside of the device. Such construction is costly and requires considerable hand work on each individual piece of apparatus. Furthermore, the use of heavy castings makes difficult the use of adequate insulation and the devices so constructed are inefficient for this reason and for the further reason that large masses of metal must be heated in addition to the material being sterilized. Furthermore, when uninsulated steam lines are run on the outside of the apparatus, and hence subjected to room temperature, there is a marked tendency for steam to condense within the passages so exposed, which condensation leads to difficulties in operation arising from corrosion, hydraulic ram effects, and injury to pressure operated valves and gauges.

Another deficiency often encountered in previous apparatus of the class described arises from the fact that the generally accepted construction provides separate controls for controlling the heat applied to the steam boiler and discharging steam from the sterilization chamber.

With a view to overcoming the foregoing deficiencies it is a major object of my invention to provide an autoclave construction which makes possible the use of sheet metal parts and efficient insulation.

It is another object of my invention to provide passages for live steam which are integral with the structure and avoid the harmful effects of condensation previously described.

Still another object of my invention is to provide multiple steam passages thereby reducing the possibility of plugged steam lines and the consequent danger to operating personnel.

A further object of my invention is to provide a sterilization chamber which conforms to the general shape of laboratory packs of surgical dressings and the like, hence making economical use of the volume available.

Still another object of my invention is to provide a liner for the sterilization chamber of an autoclave which is readily removable for repair or replacement.

An additional object of my invention is to provide for coordination of the boiler heat and steam discharge controls whereby to materially reduce the possibility of injury to operating personnel and damage to the equipment occasioned by boiling away the contents of the boiler.

The foregoing and other objects and advantages of my invention will become apparent from

2

a consideration of the following detailed description taken in connection with the attached drawings in which:

Fig. 1 is a perspective view of an autoclave embodying my invention;

Fig. 2 is an elevational section taken on the line 2—2 in Fig. 1;

Fig. 3 is an elevational section taken on the line 3—3 in Fig. 2;

10 Fig. 4 is a partial perspective view showing the system of discharge lines employed in the apparatus illustrated in Fig. 1;

Fig. 5 is an enlarged portion of Fig. 2 indicated by the dotted circle 5 therein; and

15 Fig. 6 is a wiring diagram showing interconnections between the various controls of the apparatus in Fig. 1.

Referring now to the drawings and particularly Figs. 1 and 2 thereof, the numeral 10 designates a sterilization chamber in the autoclave of my invention, the chamber having a generally square transverse cross-section and being formed with a removable liner 19, access being provided thereto through a square door 11. The door 11 is provided with a pressure proof gasket 18 and is secured against pressure in the sterilization chamber 10 by means of a screw 13 having a hand wheel 14 keyed thereto. The pressure screw 13 is threadedly engaged with a nut 15 which, in turn, is held in the center of a transverse "strong back" 12. As can be seen in Fig. 1 the right end of the strong back 12 is hingedly supported by gudgeons 71 at its right end, and is secured by a latch 72 at its left end. As indicated in Fig. 6 20 the latch 72 is mechanically linked to a line switch 90 so that unlatching the door 11 automatically breaks the power circuit. The door 11 is supported by a centrally mounted foot 17 secured thereto and rotatably mounted to the forward end of the pressure screw 13. An anti-friction bearing 16 is provided at the forward end of the pressure screw 13, and transmits the thrust of the screw to the foot 17 and hence to the center of the door 11. When the latch 72 is disengaged 25 from the strong back 12, the latter may be swung back, carrying the door 11 therewith, and giving access to the chamber 10.

An outer covering for the apparatus is provided in the form of a tubular housing 77 closed at the rearward end by a back cover plate 73 and by a front cover plate 76 at the forward end. As can be seen in Fig. 5, the front cover is brazed to a hollow door frame 75 and thus hermetically seals a passage formed in the interior thereof. The back cover plate 73 is secured in place by means of screws 74 which are threaded into suitable holes formed in the ends of tie bolts 36. The bottom of the outer housing 77 is reinforced by a plate 84 suitably secured thereto and is further provided with four supporting feet 83.

Steam to effect sterilization of material loaded into the chamber 10, is produced in a boiler 23, a sump 24 of which depends from the rear bottom surface of the device, as best seen in Fig. 2. The steam pressure chamber includes the sump 24 and the generally tubular chamber surrounding the sterilization chamber 10 and is enclosed by a pressure wall 25. The bottom of the sump 24 is provided with a suitable drain plug 85 by which the boiler may be drained when necessary. The pressure wall 25 is secured at its forward end by brazing or other suitable means, to the hollow frame 75 which surrounds the square opening in the front cover plate 76 adjacent the door 11. A removable head 35 forms a closure for the rear of the pressure wall 25 and is secured thereto by the tie bolts 36 threadedly engaged at their forward ends with nuts 64 within the hollow frame 75 and provided with securing nuts 38 at the rearward ends thereof which engage and secure the head 35. The tie bolts 36 have shoulders 37 formed on the forward ends thereof and are thereby adapted to secure the liner 19 to the hollow frame 75, a gasket 40 providing a hermetic seal between these two parts. Suitable insulation such as rock wool, transcite, or the like is fastened to the pressure wall around the boiler 23 and prevents the excessive escape of heat therefrom. The foregoing features of construction are best seen in Figs. 2 and 5.

Boiler heat is provided by a pair of immersion heaters 26 and 26a, located in the sump 24 and secured in a terminal block 81. The terminal block 81 is secured by bolts (not shown) to the pressure head 35, the heaters 26 projecting through an opening in the head and into the sump 24. A gasket 82 between the terminal block 81 and the head 35 assures an hermetic seal at this point. The heaters 26 are provided with terminals 32 for electric connection thereto, the terminals being covered by a cup-shaped housing 33 screwed to the back plate 73 as seen in Fig. 2.

As will be described later herein, the heaters are thermostatically controlled, to produce steam at a predetermined and adjustable temperature.

The construction just described makes possible the easy removal of the liner 19. By removing the back cover plate 73 and the nuts 38, the head 35 may be removed, revealing the liner, which may then be removed by unscrewing the tie bolts 36 from the forward nuts 64 in the frame 75.

When the device is in operation, sterilizing steam produced in the boiler sump 24 rises in the inner space between the liner 19 and the pressure wall 25 and enters the chamber 10 through an opening 20 in the top rear wall of the liner 19. Steam passes through the chamber 10 in a forward and downward direction as indicated by the arrows in Fig. 2, and escapes from the chamber through a series of exit ports 21 in the hollow frame 75 as best seen in Fig. 5. As will be seen in Fig. 5, the exit ports 21 carry the steam into the interior of the hollow frame 75 whence it travels upwardly through the frame and exits therefrom through various communicating passages shown in Fig. 3, and to be described in detail hereinafter.

Each of the nuts 64 secured within the hollow frame 75, is, as shown in Fig. 5, provided with an annular groove 79 in its periphery and thereby does not materially obstruct the interior passage within the frame 75.

The steam exiting from the hollow frame 75 discharges selectively through either or both of a pair of pipes 67 and 68, best seen in Fig. 4, into a condenser tube 42 which is immersed in a cold

water reservoir 41. The steam condenses in the tube 42 and flows from the upturned end thereof into the reservoir 41. The reservoir is provided with a filling cover 45 and a float 93 operated level indicator 44, which projects through the top of the apparatus in position to be viewed from the front thereof.

For a detailed description of the various control and indicating means relating to the discharge of steam from the sterilizing chamber 10, reference should now be had to Figs. 3 and 4. Mounted to the top of the frame 75 is the hermetically enclosed thermostatic valve 59, the details of which are shown in Fig. 3. The valve 59 includes a valve needle 50 supported on the lower end of the thermostatic bellows 51 of conventional design. The needle 50 is positioned to seat in a valve seat 55 which communicates with the forward end of the pipe 68. A passage 52 provides communication between the interior of the frame 75 and a chamber 54 surrounding the bellows 51 which is filled with a liquid or a gas in the conventional manner so that when heated it expands in a manner to force the needle 50 into closing engagement with the seat 55. The temperature characteristics of the material filling the bellows 51 are such that at temperatures less than that required for adequate sterilization (approximately 250° F.), the valve 59 is open, permitting the escape of air from the frame 75 through the passage 52, the chamber 54, and the seat 55 into the pipe 68. As the temperature in the chamber 54 rises, the bellows 51 expand closing the needle 50 into the seat 55 and preventing further discharge of steam therethrough. The purpose of this arrangement is to allow steam produced in the boiler 23 to force all relatively low temperature air out of the chamber 10 and through the condenser tube 42 thus assuring that the chamber 10 is filled with relatively high temperature steam before the required sterilizing pressure starts to build up in the chamber.

If as is sometimes the case it is desired to discharge the steam manually from the chamber 10 a valve 57 is provided for this purpose. As will be seen in Fig. 3, it serves to control communication between the passage 52 and the pipe 68 through a by-pass including two passages 53 and 56.

A conventional pressure gauge 61 visible from the front of the device is mounted to the top of the frame 75 and communicates therewith through passage 60.

A connection block 80 is also mounted to the top of the frame 75 and has formed therein a passage 62 which communicates with the pipe 67 as seen in Fig. 3, and also with a conventional spring loaded safety valve 63 which operates to release excessive steam pressure should the same build up in the chamber 10. As will be seen from an examination of Fig. 4, the pipe 67 communicates with the condenser tube 42 through a solenoid operated valve 69, the electrical circuit of which is interconnected with other electrical controls to be described hereinafter. When the solenoid valve 69 is opened, steam may discharge through the frame 75, the connection block 80, and the pipe 67 into the condenser tube 42. As can be seen in Fig. 6 an indicator light 92 is connected in parallel with the valve 69 and serves to indicate when steam is discharging through valve 69.

With reference now to the control of steam temperature, current to the electric heaters 26 and 26a is controlled by means of a pair of thermostats 27 and 27a which are mounted in the

forward vertical wall of the sump 24 and project into the interior thereof. The thermostats 27 and 27a and heaters 26 and 26a are connected in series-parallel as shown in Fig. 6. One of the heaters 26 is controlled by a thermostat 27 having a fixed setting slightly less than the lowest desired sterilization temperature. The other heater 26a is controlled by an adjustable thermostat 27a. The thermostats 27 and 27a may be of the liquid-filled, gas-filled bi-metal or other suitable variety and one of them, 27a, is provided with a control knob 28 mounted on the front cover plate 16 and connected to the thermostat through a shaft 29 and a pair of universal joints 30. The purpose of the control knob 28 is to adjust the thermostat 27a to cut off the supply of electric current to one of the heaters 26 when the temperature in the boiler sump 24 reaches a desired and predetermined level.

The advantage of the dual heater arrangement is that during the initial heating period when the demand for heat is high, this high demand is met by both heaters acting in unison. Thereafter, it is only necessary to maintain the steam chamber at a fixed temperature and the heat required is only that which is lost by conduction through the insulation and radiation from the outer housing. It is of considerable advantage to make use of a heater which has a maximum capacity only slightly greater than the demand since, for one thing, only a relatively small current need pass through the contacts of the controlling thermostat, and for another, wide variations in temperature during the "on-off" heating cycle are avoided. These wide variations in regulated temperature are known as "overshooting" and have been a particular disadvantage in previous apparatus of the class described since it is of extreme importance that the sterilizing temperature be maintained substantially constant. Insufficient temperature will fail to produce effective sterilization and excessive temperature may result in damage to surgical apparel, particularly rubber gloves and the like. I have found that with the control system of my invention, autoclave temperatures may readily be controlled within a maximum differential of 3°, whereas differentials of 10° or more are frequently encountered in previous apparatus.

Delivery of electric current to the heaters 26 and 26a is also controlled by means of a single pole double throw switch 31 which is mounted in the lower portion of the front cover plate 16 as seen in Fig. 1. Operation of the switch 31 also controls the delivery of electric current to the solenoid valve 69 as will be seen from an examination of the wiring diagram shown in Fig. 6, where it will be seen that when the switch is operated to turn off the heaters 26 and 26a, it simultaneously energizes the solenoid 69 thereby permitting steam to discharge through the pipe 67 and into the condenser tube 42 as previously described. Thus, when the steam is discharged from the chamber 10 by operation of the switch 31, preparatory to opening the door 11 and removing sterilized material from the chamber 10, the heaters 26 are automatically shut off, and the possibility of boiling away of the water in the sump 24 is substantially obviated.

As the supply of water in the sump 24 becomes depleted and the level therein drops, a conventional hingedly mounted float 48 swings downwardly opening a valve 49 and permitting water from the reservoir 41 to flow downwardly through a check valve 46, a tube 47, and the

float operated valve 49 into the sump 24 thus replenishing the supply of water therein. The check valve 46 prevents steam from escaping back up the tube 47 into the reservoir 41, thus water can flow through the tube 47 when the boiler is substantially at atmospheric pressure.

It is obvious that continuous operation of the device will result in loss of water in the reservoir 41, due to the escape of steam from the chamber 10 each time the door 11 is opened. To replenish the water thus lost, the filling cap 45 is provided through which the reservoir 41 may be refilled as previously described.

The autoclave embodying my invention is operated in the following manner:

Having ascertained by an examination of the scale 44 that there is sufficient water in the reservoir 41, the latch 72 is disengaged from the strong back 12, which is then swung back carrying with it the door 11 and giving access to the chamber 10. The material to be sterilized is then placed in the chamber 10, the door closed and locked, and pressure is applied thereto by means of the hand wheel 14 and the pressure screw 13. It will be noted that the locking of the latch 72 automatically closes the line switch 90 thus placing the heaters under the sole control of the control switch 31. The thermostat 27a is adjusted by means of control knob 28 to give the desired temperature of sterilization, and the switch 31 is then operated to the "on" position thus delivering current to the heaters 26. As steam is produced in the sump 24 it passes through the chamber 10 in the manner previously described, operates the thermostatic valve 59, and builds up pressure in the chamber 10. The apparatus is left in this condition for a period of time necessary to effect the desired sterilization of the material in the chamber 10, at which point switch 31 is operated to the "discharge" position. As previously described, this turns off the heaters 26 and allows the discharge of the steam from the chamber 10. When the steam has been discharged from the chamber 10 as will be indicated by the gauge 61 the door 11 may be opened and the sterilized material removed.

Should it become necessary to manually discharge the steam from the chamber 10 by reason, for example, of an electric power failure, it may be accomplished through manipulation of the valve 57 in the manner previously described.

It will be appreciated by those familiar with operation of equipment of the class described, that since the walls of the hollow frame 75 are to all intents and purposes, integral with the pressure wall 25, it is maintained at substantially the same temperature as the steam in chamber 10 and hence there is little or no tendency for steam to condense within the frame 75.

It is also obvious that steam entering the frame 75 may reach the discharge passages 52, 60 and 62 by passing upwardly through either of the vertical portions of the frame 75. Thus since a multiple passage is formed there is less likelihood of plugging the same and preventing discharge of steam from the chamber 10.

It will be noted further that, if the thermostat 27 should, for some reason, fail to control the heaters 26, resulting in the production of excessive pressures within the chamber 10 and the balance of the system communicating therewith, the safety valve 63 will operate to release steam thus reducing such excessive pressure.

While the apparatus shown and described herein is fully capable of achieving the objects

and providing the advantages hereinbefore stated, it is subject to considerable modification within the spirit of the invention and therefore I do not mean to be limited to the form shown and described herein, but rather to the scope of the appended claims.

I claim:

1. In an autoclave, the combination of: a pressure chamber having an opening therein adapted to receive material for sterilization in said chamber; a hollow frame for said opening having a passage therein communicating with said chamber; means to hermetically close said opening; means for producing live steam in said chamber; and means operatively associated with said frame to control the discharge of steam from said passage.

2. In an autoclave, the combination of: a live steam chamber adapted to receive material for sterilization therein; means in a vertical wall in said chamber forming a hollow and substantially rectilinear door frame therein, said frame having a passage throughout the peripheral length thereof having communication with said chamber adjacent the bottom edge of said frame; and valve means mounted to the top edge of said frame and having communication with the passage therein, said valve means being adapted to control the discharge of steam from said chamber through said passage.

3. In an autoclave, the combination of: means forming a pressure chamber adapted to receive material for sterilization therein; means including a water sump in said chamber and a heater in said sump to produce steam in said chamber; operable means to discharge steam from said chamber; and means responsive to operation of said discharge means to disable said heater.

4. In an autoclave, the combination of: means forming a pressure chamber adapted to contain live steam; means including a water sump in said chamber and a heater in said sump to produce steam in said chamber; an electrically operated discharge valve for said chamber; and current control means for said heater and valve adapted to selectively disconnect the former upon opening of the latter or energize the former upon closing of the latter.

5. In an autoclave, the combination of: means forming a pressure chamber adapted to receive material for sterilization therein; means including a water sump in said chamber and a heater in said sump to produce steam in said chamber; a water supply reservoir; passage forming means to discharge water from said reservoir into said sump; and control means in said passage means responsive to water level in said sump to control said discharge.

6. In an autoclave, the combination of: means forming a pressure chamber adapted to receive material for sterilization therein; means including a water sump in said chamber and a heater in said sump to produce steam in said chamber; a water supply reservoir; a water tube connected between said reservoir and sump to replenish the water supply in said sump; and a check valve in said tube to prevent passage of steam from said chamber to said reservoir.

7. In an autoclave, the combination of: means forming a pressure chamber adapted to receive material for sterilization therein and a water sump therein; a pair of heaters in said sump adapted to convert water therein into live steam in said chamber; a water supply reservoir; steam passage means formed in a wall of said pressure

chamber adapted to discharge steam therefrom; a condenser tube having communication with said steam passage means and positioned in said reservoir whereby to be immersed in water therein; and thermostatic means operatively associated with said heaters whereby one of the same is adapted to steadily deliver a portion of the heat necessary to produce said live steam and the other adapted to intermittently deliver sufficient heat to maintain the temperature of said steam substantially constant.

8. In an autoclave, the combination of: a pressure chamber having a water sump and heater in said sump to produce live steam in said chamber; a removable compartment within said chamber adapted to receive material for sterilization by said steam; means forming an opening with a pressure door in a wall of said chamber adapted to admit said material into said compartment; a hollow frame formed in a wall of said chamber surrounding said opening and having a passage therein communicating with said compartment; and valve means operatively associated with said frame whereby to control the discharge of steam from said compartment through said passage.

9. In an autoclave, the combination of: means for producing live steam; a chamber adapted to receive material for sterilization by said steam; means for hermetically closing said chamber; passage forming means integral with the wall of said chamber adapted to carry steam from said chamber; and valve means including a safety valve adapted to control the discharge of steam through said passage.

10. In an autoclave, the combination of: means forming a pressure chamber having a steam discharge passage formed integrally with a wall thereof; means including a water sump in said chamber and an electric heater in said sump to produce steam in said chamber; thermostatic control means for said heater adapted to control the pressure of steam in said chamber; and means including a valve in said passage and a switch connected to control said heater, said valve and switch being interconnected so that said valve is opened upon the de-energizing of said electric heater.

11. In an autoclave, the combination of: means forming an insulated pressure chamber with a water sump therein; means forming a passage in a wall of said chamber opening thereinto; a water supply reservoir; a condenser tube positioned in said reservoir and adapted to communicate with said passage; valve means between said passage and condenser tube adapted to control said communication; a water tube connected between said reservoir and said sump adapted to deliver water to said sump; heater means in said sump adapted to convert water therein into live steam at a predetermined pressure; a float valve responsive to water level in said sump to control water flow through said tube; and a check valve in said tube adapted to prevent counterflow therethrough due to pressure of said steam.

12. In an autoclave, the combination of: means forming an insulated pressure chamber having a water sump; means forming a passage in a wall of said chamber opening thereinto; a water supply reservoir; a condenser tube positioned in said reservoir and adapted to communicate with said passage; valve means, including a solenoid valve, between said passage and condenser tube adapted to control said communication; a water supply tube connected between said reservoir and said sump; an electric

heater in said sump adapted to produce live steam at a predetermined pressure in said chamber; a float valve responsive to water level in said sump to control water flow through said supply tube; a check valve in said supply tube adapted to prevent counter-flow therethrough due to pressure of said steam; and switch means connected between said heater and solenoid valve adapted to disconnect the former upon opening the latter.

13. In an autoclave the combination of: means forming a pressure chamber adapted to receive material for sterilization therein; boiler means including a pair of heaters adapted to produce steam for delivery to said chamber; thermostatic means including separately adjustable sensing elements connected to each of said heaters whereby one of said heaters is adapted to deliver an amount of the heat necessary to initially heat said chamber to a predetermined temperature, and the other of said heaters is adapted to intermittently deliver an amount of the heat necessary to maintain said chamber always above said predetermined temperature.

14. In an autoclave, the combination of: means forming a pressure chamber adapted to receive material for sterilization therein; a boiler adapted to produce live steam for delivery to said pressure chamber; a pair of heaters for said boiler; first thermostatic control means operatively connected with a first of said heaters whereby the same is adapted to raise said boiler means to a temperature slightly less than that desired for sterilization; and second separately adjustable thermostatic control means operatively connected with the other of said heaters whereby the same is adapted to increase said temperature over that produced by said first heater to a degree desired for sterilization.

15. In an autoclave, the combination of: a pressure chamber adapted to contain live steam; removable liner means forming an inner compartment in said chamber adapted to receive material for sterilization therein; means forming a passage integral with a wall of said chamber adapted to discharge steam from said compartment; valve means in said passage to control said discharge; boiler means including a pair of heaters adapted to produce steam for delivery into said compartment; discharge control means adapted to selectively open said valve means while disabling said heaters or to energize said heaters upon closing said valve means; thermostatic means including a separately adjustable control element for each of said heaters whereby one of the same is adapted to initially heat said boiler means to a predetermined temperature and the other to intermittently deliver heat to said boiler means, whereby to maintain the same at a relatively constant temperature of sterilization; and water supply means for said boiler means responsive to the water level therein to deliver water thereto through said supply means including a check valve to prevent counter-flow therethrough due to pressure of steam in said boiler means.

16. In an autoclave, the combination of: means forming a pressure chamber having live steam therein, said chamber having a rectangular forward opening, a rear opening, a removable pressure head secured in said rear opening normally to close the same, and a hinged door for said forward opening; and a liner for said

chamber having a generally rectilinear cross-section whereby the same is adapted for alignment with said forward opening to receive generally rectilinear packs of material for sterilization in said liner, the latter being removably secured to the inner wall of said pressure chamber adjacent the edges of said forward opening and forming a sterilization chamber within said pressure chamber, the transverse and vertical dimensions of said liner being less than those of said rear opening whereby said liner may be removed and inserted through said rear opening.

17. In an autoclave, the combination of: a pressure chamber having a loading opening to receive material for sterilization in said chamber and a movable closure for said opening to hermetically seal said chamber; means including a water sump in said chamber and a heater in said sump to produce steam in said chamber; and means responsive to the movement of said closure to disable said heater when said chamber is unsealed.

18. The construction of claim 17 further characterized in that said heater is electric and said disabling means includes a switch mechanically connected to said closure.

19. In an autoclave, the combination of: a pressure chamber having an opening therein adapted to receive material for sterilization in said chamber; a removable liner in said chamber spaced from the walls thereof and aligned with said opening to receive said material therethrough for support in said liner during said sterilization, said liner having an opening to receive steam from said chamber; a hollow frame for said opening having a passage therein communicating with the interior of said liner to discharge steam therefrom; means to hermetically close said opening; means for producing live steam in said chamber; and means operatively associated with said frame to control the discharge of steam from said passage.

20. In an autoclave, the combination of: a live steam chamber having a vertical wall and an opening in said wall to receive material to be sterilized; a liner in said chamber removably secured to said wall, spaced from the other walls of said chamber, and aligned with said opening to receive said material for sterilization in said liner, the latter having a top opening to receive steam from said chamber; closure means to hermetically seal said opening; means forming a passageway in said first chamber wall, said passageway having an opening into said liner adjacent the bottom thereof to discharge steam therefrom, said passageway being in intimate heat transfer contact with said first wall whereby to inhibit the condensation of steam in said passageway; and valve means in said passageway to control said discharge of steam.
